UNITED STATES PATENT OFFICE.

RICHARD PATRICK WALSH, OF ST. LOUIS, MISSOURI.

GRIP-PULLEY WHEEL.

SPECIFICATION forming part of Letters Patent No. 400,276, dated March 26, 1889.

Application filed February 27, 1888. Serial No. 265,369. (No model.)

To all whom it may concern:

Be it known that I, RICHARD PATRICK WALSH, a citizen of the United States, residing at St. Louis, in the State of Missouri, have invented certain new and useful Improvements 5 in Grip-Pulley Wheels, of which the following is such a full, clear, and exact description as will enable any one skilled in the art to which it appertains to make and use the same, reference being had to the accompanying drawings, forming part of this specification.

My invention relates more especially to improvements in the means for imparting the motion of the machinery of the power-house 15 to the cable of a cable railway, and dispenses with the grooved sheaves which impart such motion to the cable, and substitutes therefor a sheave having clamping mechanism thereon of peculiar construction, which clamps 20 the cable to said rotating sheave and imparts motion thereto, the said cable, when it reaches the tangential points of said sheave, being clamped at the point where the cable runs on the said grip-pulley, and unclamped there- 25 from at the point where the cable runs from said grip-pulley, the clamping and unclamping being performed automatically by the rotation of the grip-pulley itself. By this means a positive grip is applied to the cable at 30 the power-house, so that the motion of the driving mechanism at said power-house is positively applied to the cable and all slipping prevented.

Other objections by my mechanism are also 35 obviated, which I will now proceed to set forth.

In the construction of power-house plants as now generally used the motion is imparted to the cable by two revolving grooved sheaves 40 which are provided with a multiplicity of grooves. The cable passes over these grooved sheaves, which are rotated constantly by the engine a number of times, and from thence proceeds to the tension-regulating device. A 45 powerful tension is put upon the several turns of the cable between these grooved sheaves, so as to increase the friction between the cable and the sheaves, to prevent slipping of the cable and to cause the motion of the 50 sheaves to be imparted to the cable. I have discovered that it is this extreme tension between these sheaves that destroys the life of

the cable and produces a permanent set in the same, so that it becomes, so to speak, lifeless, and often disrupted in some of its strands. It 55 is popularly supposed that cables are destroyed when in the conduit and when performing their functions in drawing cars. The strain placed upon cables when in the conduit is nothing to compare with the strain 60 thrown upon cables when between the grooved sheaves before spoken of. It is my opinion and belief that cables are destroyed by the tension and other troubles that arise from the use of the mechanism now generally employed in power-houses to impart motion to 65 cables. These grooved sheaves in cable railways have inherent objections, in that it is impossible to make the several grooves in said sheaves of the same depth, so as to have them 70 mathematically correct. The grooves are liable to vary, even when the best workmanship is employed in making them, from an eighth to a sixteenth of an inch, so that an increased tension is placed upon the cable by 75 this variation in depth of the grooves. The variation spoken of produces a strain on the cable in proportion to the diameter of the sheave, so that with a sheave of large diameter the increased strain due to the variation 80 in the grooves is something enormous to contemplate. It is this feature which produces the great strain upon cables and gives a cable a permanent set. My invention dispenses, as before remarked, with the grooved sheaves 85 and overcomes entirely any increase of strain due to variation in the grooves of such sheaves.

Another feature which I wish to call attention to in connection with the use of grooved sheaves is that the cable in passing over the 90 same is being bent back and forth at a rapid rate, the effect of which, as is well known, is to disrupt the wire of the strand, producing molecular disturbances in the metal thereof. This difficulty is increased, of course, in proportion to the number of turns between the sheaves, so that with a great number of turns the life of the cable is necessarily shorter. In my invention I do away with this multiplicity of turns of the cable and reduce the 95 same to a minimum—namely, one turn—so that the bending of the cable in passing over the sheave is also reduced to a minimum and the life of the cable prolonged thereby.

Another feature which may be mentioned in this connection is, that where grooved rollers are employed, and the cable passes over the same a multiplicity of times, the cable necessarily must travel a great deal farther on the sheaves during the space of a month or a year, for instance. It may be remarked, then, that with grooved sheaves the cable has to travel a greater distance on the sheaves, and therefore is subjected to more wear, and its life is thereby rendered correspondingly short. In my invention the cable makes but one turn in passing over the sheave, so that the travel of the cable on the sheaves is reduced to a minimum, and its life, in consequence thereof, reaches a maximum.

I will proceed now to describe an apparatus embodying one form of my invention by referring to the accompanying drawings, in o which—

Figure 1 is an elevation of my clamp cable driving wheel or sheave. Fig. 2 is a section on the line 2 2 of Fig. 1. Fig. 3 is a side elevation of the cam for operating the clamping mechanism, showing also the clamping-wheel shaft with the clamp-wheel removed. Fig. 4 is a sectional plan of the latter on the line 4 4 of Fig. 3. Fig. 5 is a face view of the guide bearing-wheel which is attached to the o clamp-wheel shaft. Fig. 6 is a section thereof on the line 6 6. Fig. 7 is an isometric projection of one of the bearings on the guide-wheel. Figs. 8 and 9 are detail views showing the rim of the clamp-wheel with a clamp in different positions. Fig. 10 is a side elevation showing the relation of the clamp-wheel, the engine-shaft driving the same, the idle-wheel, and tension-carriage, having the clamp connecting-rods and cam-operating o disk removed from the grip-pulley for the sake of clearness, showing also the path of the cable. Figs. 11, 12, and 13 are isometric projections of the details of a clamp. Figs. 14 and 15 are views of the clamping-rods, Fig. 14 being a section on the line 14 14 of Fig. 15.

Referring to Fig. 10, 1 is the main or driving shaft of the engine. 2 is a spur-wheel thereon, which meshes with wheel 3, secured o to a hub, 4, mounted upon a counter-shaft, 5.

Referring now more particularly to Figs. 1 and 2, 6 is a rim or annulus attached to the wheel 3, to which rim the clamps 7 are secured. The rim 6 is preferably bolted to the 5 wheel 3, as shown in Figs. 8 and 9.

In the construction now employed the grooved sheaves over which the cable passes are arranged on a shaft which is turned by a wheel keyed to said shaft at considerable distance from said grooved sheaves. Motion is imparted to this wheel by any suitable means, but usually by a pinion on the engine-shaft gearing into said wheel. In such a construction a twisting strain is put upon the shaft 5 which carries the grooved sheaves and the wheel. The greater the distance of the sheaves from the wheel the greater will be

the strain thrown upon the shaft. In my construction I avoid this by practically making the sheave for the cable and the driven 70 wheel in one. I do this, as pointed out before, by bolting the rim 6, which forms the sheave for the cable, to the wheel 3, which is driven by the pinion 2, located upon the engine-shaft 1. (See Figs. 2 and 10.) I thus 75 practically obviate the twisting strain which is usually thrown upon the shaft 5, and thus secure an advantage over these previous constructions. So far as I am aware I am the first to do this. The clamps 7 consist of several parts, which are shown in Figs. 11, 12, and 13.

8 is the clamp-shoe, which is attached to the clamp.

9 is a bifurcated piece which straddles the 85 clamp 7, the said clamp 7 being journaled to the piece 9 by a rod passing through perforations in the two parts, the perforation in the part 9 being eccentric to the journals 10 10, which are supported by bearings or pillow-blocks 11 11, attached to the rim 6. The clamps 7 are arranged around the rim 6 at equidistance, each being supported in its own bearings 11 11, secured to said rim. The clamp 7 is also provided with a lug, 12, integral with 95 the same.

From the bifurcated piece 9 run rods 13 to a guide-wheel, 14, and from the part 12 of the clamps 7 also run rods 15 to the guide-wheel 14, the one set of rods being arranged directly 100 over the other. The guide-wheel 14 is secured to the hub 4 and revolves with the wheel 3 and rim 6. It is provided with a series of radial bearings, 16, near its periphery, and is also provided with a series of radial guides, 17, 105 midway between the center and the bearings 16. The rods 13 are guided by the bearings 16, and the rods 15 pass through and below the bearings 16 to the guides 17, as clearly shown in Figs. 6 and 7. The plate 31, Fig. 7, 110 forms the other side of the bearings 16, the said plate being removed to show the construction more clearly. The rods 13 and 15 are provided with rollers 18 and 19, respectively, at their inner ends. 115

Supported from the foundation of the apparatus is a stationary cam-disk, 20, which is provided with two cams, 21 22, each being formed by two rims projecting at right angles from the stationary cam-disk, making a groove 120 between each of the two rims, in which grooves the rollers 18 and 19 travel as the wheel 3 revolves. The cam-disk is supported by plates 32 32, which are bolted to the foundation of the plant. 125

It will be noted that when the wheel 3 revolves, carrying with it the clamps and rods 13 and 15, the guide-wheel 14 will also be carried around at the same time, as it is rigidly secured upon the hub 4, which is keyed 130 to the shaft 5. The rollers 18 and 19 will therefore be caused to travel around in the cams 21 22, and will operate the rods 13 and 15, as the clamp-wheel revolves in the direc-

tion of the arrows in Fig. 1. As the upper part of the wheel passes the line 2 2, the clamps will be taken off of the cable. The cam 21, operating ahead of the cam 22, draws 5 the rods 13 toward the center, as shown in Fig. 8. This revolves the eccentric in the direction of the arrow shown in said latter figure and takes off the pressure of the clamp 7 upon the cable 23. The pressure being removed, the cam 22 begins to act, draws down 10 the rod 15, (see Fig. 8,) and swings the clamps 7 out of the plane of the rim 6 into the position shown in Fig. 9, so that the cable can leave the wheel at the tangential point. The 15 clamps stay thrown back in the position shown in Fig. 9 until they approach the line 2 2 again in their revolution. When the cam 22 acts in pressing the rods 15 outward and throwing the clamp into the position indicated in the dotted lines of Fig. 9, the cam 21 20 begins to act and pushes the rods 13 outward, moving the eccentric in the direction of the arrow in Fig. 9, and drawing the clamp 7 down upon the cable into the position shown in Fig. 8, tightly clamping said clamp against the 25 cable and rim 6, attached to the wheel 3. The clamps are held in engagement with the cable until they pass the line 2 2 again, when the same operation is repeated.

30 The rods 13 15 are provided with a spring-socket or elastic connection, 24, in order to render their operation and adjustment more perfect. Were the rods 13 unprovided with such spring-sockets, too great a pressure might 35 be placed on the cable, or the rods might be torn asunder by the great stress thrown upon them. Within the socket 24 is a stout spiral spring 40 which bears against a head, 25, connected to one end of the rod and playing up and down against the tension of the spring in the socket through the cap-piece 26. The other ends of 45 the rods are screw-threaded and screwed into a sleeve, 27, which engages a screw-thread, 28, on the inside of the socket 24, so that when any undue pressure is thrown upon the 50 rods it will be taken up by the spiral spring through the play of the head 25. These spring-sockets render a nice adjustment of the parts unnecessary, as they will compensate for any 55 irregularity in adjustment and operation.

29 (see Fig. 10) is the idle-wheel, the axle 31 of which is slightly inclined, so that the cable can be passed to the tension device without interfering with the wheel 3—that is to say, 55 the wheel 29 is thrown slightly out of the plane of the wheel 3. The cable 23 leaves the conduit in the direction of the arrows, passes to the clamp-wheel with one turn, to the idle-wheel, and thence to the tension device 30, 60 and out again to the conduit in the direction of the arrows.

It will be noted that I dispense entirely with grooved sheaves referred to above, and substitute therefor a clamping-wheel, which 65 is more efficient in imparting motion to the cable, and that I throw no extra strain upon the cable to impart such motion to it, the

only strain put upon the cable being that due to the useful work it performs. I therefore effect great economy in the operation of cable 70 railways, wasting little or no energy in unnecessary friction and strain.

It will be observed that the clamping mechanism is entirely automatic in action, that the mechanism can be made durable and strong 75 and is not complicated, and, as pointed out above, it will prolong the life of a cable much beyond its usual period of existence, and inasmuch as it will do this it will save many thousands of dollars. 80

Having now set forth my invention and described its operation and advantages, I wish to have it known that I do not limit myself to the exact mechanism described, as the same may be varied in many ways without departing from the spirit of my invention. 85

What I desire to claim, and secure by Letters Patent of the United States as my invention, is—

1. The combination of a driven wheel, a 90 cable passing therearound, clamps carried by said driven wheel, two series of rods connected to said clamps, a guide-wheel holding said rods in position and revolving with said driven wheel, and cams controlling said rods 95 to intermittently clamp the cable to the driven wheel, for the purpose described.

2. The combination of a driven wheel, a 100 cable passing over said wheel, clamps intermittently clamping said cable to said wheel, 100 rods having elastic sockets in them intermediate of their ends, which rods are connected to said clamps, and a disk having cam-grooves controlling said rods, whereby 105 said elastic sockets compensate for any irregularity of adjustment and operation and prevent undue pressure being thrown upon the cable.

3. A grip-pulley wheel having clamps arranged around the periphery thereof, rods 110 connected to said clamps, and a stationary disk with cam-groove controlling said rods, whereby the cam-disk puts on and takes off the clamps.

4. A grip-pulley wheel having clamps arranged around the periphery of said wheel, 115 two rods connected to each clamp, one of which rods throws said clamp in and out of the plane of the cable, and the other of which raises said clamp and draws it down upon said cable, 120 and a disk having cam-grooves controlling said rods.

5. A grip-pulley wheel having clamps pivoted in movable bearings journaled in the periphery of said wheel, a rod connected to 125 the clamp, a second rod connected to said movable bearings, whereby the clamps are swung into and out of the plane of the cable and the cable is clamped and unclamped, and a disk having cam-grooves controlling said 130 rods.

6. A grip-pulley wheel having clamps pivoted in movable bearings journaled in the periphery of said wheel, rods for said clamps,

- a stationary disk provided with cam-grooves which control said rods, and a guide-wheel revolving with said grip-pulley, substantially as described.
- 5 7. The combination, substantially as hereinbefore set forth, of the driven wheel 3, carrying the clamps 7, journaled in the bifurcated piece 9, the rods 13 15, connected to said bifurcated piece 9, and the clamps 7, respectively, a disk having grooves controlling said rods, a cable, and a guide-wheel, 14.
8. The combination, substantially as hereinbefore set forth, of the wheel 3, driven by the gear-wheel 2, the rim 6, carried thereby, 15 the clamps 7, as described, journaled on said rim, the rods 13 15, the guide-wheel 14, mounted on the hub of said wheel 3, a stationary disk carrying the cam-grooves 21 22, controlling said rods, and clamps to intermittently 20 clamp the cable.
9. The combination, substantially as hereinbefore set forth, of the driven wheel 3, the rim 6, secured to the same, the clamp 7, carried by said rim and mounted in the part 9, 25 the rods 13 and 15, the guide-wheel 14 for said rods, a spring-socket in said rods, rollers carried by said rods at their inner ends, and a cam-disk, 20, bearing the two cam-grooves 21 22, in which said rollers travel, as and for the 30 purpose described.
10. The combination, as hereinbefore set forth, of the wheel 3, clamps 7, pivoted in the bifurcated pieces 9, journaled eccentrically in the periphery of said wheel, a rod connected with said bifurcated piece, a rod 35 connected with said clamp, a guide-wheel revolving with the aforementioned wheel, forming bearings for said rods, and a stationary disk having two cam-grooves controlling the two series of rods.
11. The combination of a wheel, as 3, a cable, and a grip-pulley therefor secured directly upon said wheel, for the purpose described.
12. The combination of the spur-wheel 3, a 45 rim, 6, mounted upon said wheel, forming a pulley for a cable, clamps for intermittently clamping said cable to said rim, and a pinion-wheel for driving said spur-wheel intermeshing with the same, substantially as and for 50 the purpose described.

In testimony whereof I have hereunto set my hand, this 23d day of February, 1888, in the presence of the two subscribing witnesses.

RICHARD PATRICK WALSH.
